HAIR CUTTING DEVICE

William H. Onion, New Orleans, La.

Application February 26, 1934, Serial No. 713,055

3 Claims. (Cl. 30—13)

This invention relates to improvements in hair cutting devices, and its objects are as follows:—

First, to provide a hair cutting device in the form of a scissors having its blades reversed 5 from the customary order and having a comb mounted on the blades' pivot in such a manner that a pair of screws threaded through one of the blades, when separately adjusted, will in turn adjust the comb, said screws having swivel 10 connections with the comb back.

Second, to grade the teeth by forming one end of the comb on an angle so as to permit trimming short hair, in other words, bend the tip portion of the comb back toward the plane of the scissors 15 and make the teeth contained by said portion of lengths diminishing toward the tip end.

Third, to incline or blend the teeth of the comb at an angle with respect to the plane of the back 20 of the comb and the blade on which the back is mounted.

In the drawing:—

Figure 1 is a plan view of a scissors modified and provided with a comb in accordance with the invention, the scissors being viewed from the 25 side which goes next to the hair in the operation of cutting.

Figure 2 is a section taken on the line 2—2 of Figure 1.

Figure 3 is a section taken on the line 3—3 of 30 Figure 1.

Figure 4 is a view similar to Figure 1, illustrating the modification in the form and mode of mounting the comb.

Figure 5 is a section taken on the line 5—5 of 35 Figure 4.

Figure 6 is a diagrammatic sectional view of another modification presently described.

The underlying purpose of the invention is that of hair cutting on human beings and on 40 animals, and for whatever other purpose the device may be adaptable, and to enable doing the cutting with a nicety and ease that will permit even an unskilled person to approach the skill of a barber. The device is intended to be operated by either right or left handed persons, and one of the chief objects is to bring the comb into close contact with the skin, and to permit 45 such adjustments of it with respect to the blade that the hair can be cut to any desired degree of closeness.

Attention is directed to the drawing in which the device is generally designated 1 in each of the chief modifications in Figures 1 and 4. The device includes flat (or substantially so) scissors 55 blades 2, 3 which are pivoted together by a pin 4

or any other substitute which will serve the purpose of a pivot. The device also includes a comb 5 which lies flat on one of the scissors blades.

The scissors is reversed from the customary order and cuts in the opposite way. The hair must be cut upwards or against its natural inclination. The blade 2 is superimposed on the blade 3, and is herein to be regarded as the bottom blade. This is the blade that goes next to the skin and hair in the cutting operation. 10

In an ordinary scissors the blade 3 would be the bottom blade, and if the comb were mounted on this blade so as to bring it next to the hair, the sweep of the comb would be downward with the hair, in which operation it would be practically impossible to do any cutting. By mounting the comb on the bottom blade of the reversed scissors, the comb will come next to the hair where it belongs, and the stroke of the teeth will be upward into the hair. 15

If the comb were similarly mounted on the blade of an ordinary scissors as already pointed out, the teeth would either point in the wrong direction or if the scissors were held so as to make them point in the right direction the other blade 25 would be interposed between the comb and the skin, thus establishing a space which would make it impossible to do accurate hair cutting. 20

A hole 6 (Fig. 2) in the back 7 of the comb receives the reduced tip 20 of the pin 4. The hole 30 is over-sized by tapering it so as to provide ample room for the back 7 to rock freely when the comb is adjusted by the screws 8, 9. The pin 4 includes a shoulder 21 (Fig. 2) which acts as a head when the nut 22 is tightened on the reduced 35 threaded end of the pin. The screws 8, 9 are suitably swivelled onto the back 7 as at 10 (Figs. 2 and 3), the holes which accommodate the swivel ends of the screws 8, 9 being large enough to enable the rocking of the back 7. Said screws 40 are threaded into the blade 2, and when the handles 11 are turned the screws are fed either forwardly or reversely so that the back 7 is rocked, so to speak, in the direction of the length of the blade 2 thereby to set the teeth 12 in the desired 45 position with respect to the blade.

In some instances it is desirable to fix the teeth 12 on a slant with respect to the back 7 (Fig. 3), in other words, bend them away at an angle from the plane of the back. This brings the points of 50 the teeth a little closer and more sharply against the skin. This slanting is not always adopted, as in the case of Figure 4.

The modification in Figure 4 is identical in principle with that in Figure 1. Similar parts 55

are denoted by corresponding reference characters distinguished by the exponent letter *a*, the only exception being the general designation 1 mentioned originally. The comb 5^a is made adjustable with respect to the blade 2^a, but this time crosswise of the blade instead of longitudinally. The crosswise adjustment is a substitution for the slanting of the teeth 12 in Figure 2.

Small plates 13 are affixed to the blade 2^a in any suitable way (Fig. 5). These have upstanding ears 14 through which screws 15, or the like are driven into the ends of the comb back 7^a as at 16 (Fig. 4) to provide pivotal mounts. The screws are fast in the comb back, but they are loose in the ears 14 so that the comb is readily turned upon adjustment of the screws 8^a, 9^a (Fig. 5).

In Figure 1 the teeth 12 are all of the same length whereas in Figure 4 they are progressively shortened toward the point of the scissors. This grading of the teeth on an angle permits finer hair cutting, especially the trimming of short hair.

Figure 6 is a diagrammatic section which is intended to illustrate how the comb is to be curved or bent at 17 away from the plane of the back and toward the point of the scissors at a place where the teeth begin to shorten. Such a place would occur approximately at 18 in Figure 4. The teeth are not shown in Figure 6, but the reader will understand that they jut out from the back 7^b away from the observer or into the paper, so to speak. The blade on which the comb is mounted is designated 2^b, the blade pivot 4^b, and the adjusting screws 8^b, 9^b. In each of the three forms of the invention it is intended to make it possible to mount a comb upon either of the two blades of the scissors. For this purpose, the blade which, according to the present showing, is idle insofar as carrying a comb is concerned is provided with holes 19 (each modification), spaced as individually required, to take the various kinds of means used in making the mounting. A comb for cutting the hair either shorter or longer than possible with the comb 5, 5^a would be attached at 19, and since a comb mounted upon either blade would be in the same relative position with respect to the scissors the latter is adapted for use by a right-handed operator in each case. In order to adapt the scissors to a left-handed operator it is intended to mount the comb, for example 5 (Fig. 1) on the opposite side of the same blade. The comb would have the same type of back illustrated in Figure 1, and in order that the screw 9 may make connection with the back in the same position shown but on the opposite

side of the respective blade, it would be the other end of the pivot pin 4 that would go through the comb back 7, and not the reduced tip 20.

The operation

is readily understood. Take the device in Figure 1 (or Figure 4) in the right hand. The thumb goes into the thumb hole of the blade 3, and one of the fingers into the hole of the blade 2. This places the comb 5 in the proper and natural position to enter the hair when the device is brought into the cutting operation. As the hair is caught up by the comb the scissors is closed, and cutting commences. For fine and more delicate cutting the type in Figure 4 has an advantage over the type in Figure 1 in that the teeth near the point of the scissors are slanted.

In all cases the comb is pivotally mounted on one or the other of the two blades of a scissors in which the blades are reversed as compared with an ordinary scissors. This brings the comb next to the skin in the use of the device in a natural cutting operation. The adjustment is such that the comb can be set at any of various angles with respect to its blade, the adjustment being made by the screws 8, 9 and locked by said screws when turning of the latter is ended. In other words, the screws will not turn of their own accord, the threads which enable the advance of the screws in either direction also preventing advance when the screws are not turned.

I claim:—

1. A hair cutting device comprising scissors blades, a pivot connecting the blades, said pivot including an upstanding tip, a comb having its back superimposed on one of the blades lengthwise and having a hole through which the tip is fitted thereby providing a pivotal mount for said back, and a pair of screws for the comb, threaded through said blade on opposite sides of the pivot, said screws having swivel connections with the back for separate adjustment of said screws.

2. A hair cutting device comprising a scissors, a comb and means by which its back is mounted on one of the blades, the teeth of said comb being bent away at an angle from the plane of the back.

3. A hair cutting device comprising a scissors, a comb consisting of a back and teeth, some of the teeth at one end of the comb being of lengths diminishing toward said end, that portion of the comb back having the diminishing teeth being bent toward the plane of the scissors, and means by which the comb is mounted on the scissors for transverse adjustment.
